UNITED STATES PATENT OFFICE.

WILLIAM SCIPIONI, OF WINNETKA, ILLINOIS.

LOCK.

Application filed May 6, 1925. Serial No. 28,434.

This invention relates primarily to locks of the multi-bolt type commonly used in safe doors, although it is equally applicable to the ordinary single sliding bolt lock, the principal objects being to provide a novel, key-operated lock the working parts of which may readily be re-arranged to necessitate a different key to operate the lock, and also a lock which will require a plurality of turns of the key to shift the bolt.

The invention further resides in a key having a plural-lug bit, the lugs of which are interchangeable according to the relative change made in the lock parts.

15 Further, the invention resides in the features of construction, and the arrangements and combinations of parts hereinafter described and claimed, reference being had to the accompanying drawings, wherein—

20 Figure 1 is a reduced showing, in elevation, of the improved lock;

Figure 2 is a view thereof with the cover of the lock casing removed and the bolts depicted in their operative position;

25 Figure 3 is a similar view showing the bolts retracted to their inoperative position;

Figure 4 is an irregular transverse section on line 4—4 of Figure 3;

30 Figure 5 is a fragmentary view, in elevation, illustrating the key acting to arrange the tumblers to permit movement of the lock bolt;

Figure 6 is a similar view depicting the lock bolt in its midway position;

Figure 7 is detailed section on line 7—7 of Fig. 5;

Figure 8 is a fragmental perspective view of the tumbler casing with the several tumblers projecting therefrom;

Figure 9 is a perspective view of the key with the lugs or bits disassembled; and

Figure 10 is a perspective view of the key-engaged portion of the locking bolt.

45 Referring more in detail to the accompanying drawings, the lock casing 1 has its cover 2 secured thereto, as by fasteners 3. A main bolt 4 is slidably mounted in the casing with its shank 5 extending beneath the lock tumblers and equipped with spaced racks 6 on opposite edges of the shank in longitudinal offset relation. These racks engage pinions 7 journaled in the casing 1, and also in the slots 8 of the shank 5, for driving them and, through the pinions, the

auxiliary bolts 9 which have shank-racks 10 meshing with said pinions, as illustrated. The shanks of the auxiliary bolts are limited in their sliding movement by the pin and slot connections 11 with the casing, the journals for the pinions cooperating with the slots 8 to restrict the sliding of the main bolt.

A tumbler housing 12 is arranged within the lock casing 1 and from its lower opened end the several tumblers 13 slidably project, being limited in their movement by the screw 14. Each tumbler is provided with a slot 15 opening through one edge thereof and each slot has a pair of recesses 16 and 17 designed to receive the lug 18 carried by the bolt shank 5. The tumblers are backed by springs 19 which urge them to a normal locking position wherein the slots 15 are out of registry with each other with the exception of the recesses 16 and 17. Thus, the lug 18 can not be moved until the slots 15 are brought into relative registration.

This registering of the tumbler slots is effected by a key comprising a stem or shank 20 having a squared or non-circular sectioned portion 21 designed to receive the hubs of a plurality of tumbler lugs 22 and a bolt-shifting lug 23. The lugs 22 have suitable indicia thereon corresponding to 85 similar marks on the tumblers, as indicated at 24, by which the lugs may be related to their respective tumblers so that the tumblers will be shifted by the key to an extent to effect registry of the tumbler slots. By this provision, the lugs 22 may be removed and rearranged to provide another combination which, of course, will necessitate a corresponding rearrangement of the tumblers. The lug 23 is 95 designed to engage the shoulders 25 and 26 of the main locking bolt 4 to shift the latter in successive steps in either direction. The several lugs 22 and 23 are secured on the shank 21 by a nut 27.

100 In operation, to unlock the door, or other closure, the key is rotated in the direction of the arrows in Figs. 5 and 6. The initial turning movement of the key arranges the tumblers with their slots in registry and also opposite the bolt lug 18, or from the position of Fig. 2 to the position of Fig. 5. Continued turning of the key causes its shank-engaging lug 23 to impinge on the adjacent shoulder 25 and slide the bolt 110

to the position of Fig. 6 when it will move out of engagement with said shoulder and shank, and permit the tumblers to again drop, and the lug 18 to engage in recess 16. Thus in this midway position, the bolt will still be operative. The turning of the key is continued whereupon the lugs 22 will again register the tumbler slots and position the lug 18 for further movement in the slots, 10 which is accomplished by the shank-engaging lug 23 acting on shoulder 26 thereby completing the shifting of the bolt to fully unlocked position where it is secured in recess 17 by the tumblers assuming normal 15 position as the key lugs 22 move away from the tumblers. A reverse double turning of the key will shoot the bolts to full locked position.

The improved lock not only affords many 20 combinations and arrangements of the lugs and tumblers, but it is especially useful in safeguarding against an unauthorized holder of a key gaining admission. Thus, should the key be lost it will only be necessary to 25 obtain another key and rearrange the lugs and correspondingly rearrange the tumblers.

By this rearrangement the lost key if found by a stranger, will not operate the lock.

What is claimed is:

A lock of the character specified comprising a casing, a main locking bolt carried thereby and having a lug and a plurality of notches defining contact walls for engagement by the main actuating cam of a key, a housing at right angles to said main locking bolt and having a plurality of separate interchangeable tumblers in the form of plates extended across said main locking bolt and having transverse slots adapted for registration to receive said lug, each plate being provided at opposite sides of the slot therein with pairs of lateral branches to receive the lug of said main locking bolt to hold said bolt in a fixed position, the forward portions of said plates being adjacent the notches in said bolt and adapted for engagement by the cams of a key whereby the plates may be moved longitudinally for aligning the transverse slots therein.

In testimony whereof I affix my signature.

WILLIAM SCIPIONI.
